UNITED STATES PATENT OFFICE.

WILHELM KOCK, OF CINCINNATI, OHIO, ASSIGNOR TO JOSEPH L. HALL,
OF SAME PLACE.

COMBINED TIME AND NON-TIME LOCK.

SPECIFICATION forming part of Letters Patent No. 272,063, dated February 13, 1883.

Application filed July 10, 1882. (Model.)

To all whom it may concern:

Be it known that I, WILHELM KOCK, of Cincinnati, Hamilton county, Ohio, have invented a new and useful Time and Permutation Lock, 5 of which the following is a specification.

This invention is an improvement in locks whose "combination" or "permutation" mechanism is capable of being subjected to temporary control of clock-work.

10 The principal useful novelties of this invention are comprised in two parts, to wit:

The first part of my invention relates to a location of the timer motive apparatus—main spring and its accessories—on the outer side of 15 the safe-door, so as to be accessible for manipulation or repair in case of premature stoppage, either from fracture, or from giving out of the mainspring, or from other cause.

The second part of my invention relates to 20 a mechanical expedient whereby, in event of the loss, forgetfulness, or misunderstanding of the "combination formula," the clock-work, at some predetermined period—say three hours after release of the combined detached lever 25 and angle-bar—operates to disengage the detached lever from the angle-bar, so as to permit the lock to be opened without setting up the combination.

In the accompanying drawings, Figure 1 is 30 an inside elevation of the lock as it appears after the following operations, to wit: the timer set for release after a lapse of ten hours from winding up, the bolt thrown, and the combination gated. In this view the "automatic" pin is shown set for holding back or delaying the domination of the timer for a specified time—say two hours. Fig. 2 is a transverse section on the line 11. Fig. 3 is a similar elevation in which the spring-detent *c* is shown 35 temporarily retracted by the automatic pin. Fig. 4 is a top view of the fence or dogging mechanism, the parts being in position they occupy in Fig. 3, and the upper safe-bolt being removed. Fig. 5 is a similar elevation, showing the parts in the conditions they assume 40 after discharge of the ordinary timer functions, and with the tumblers "gated" or set up "in combination" for retracting the door-bolt. Fig. 6 is a similar elevation, showing the parts in

the positions they assume after the timer has 50 disengaged the detached lever from the angle-bar, thereby making it possible for the lock to be opened by any person by simply turning of the knob or handle, without using the combination. Fig. 7 is a perspective view, showing 55 a part of the lock-case with its pivoted angle-bar. Figs. 8 and 9 show respectively my detached lever and my connecting-latch separated from each other and from the lock. Fig. 10 represents a portion of the outside of the 60 safe-door in its unlocked condition. Fig. 11 is a front elevation of the timer motive mechanism or exterior adjunct, the barrel or housing being shown in section. Fig. 12 is a rear elevation of the exterior adjunct, the ratchet- 65 pawls being disengaged. Fig. 13 represents a portion of the outside of the safe-door, the same being in its locked condition, and the ratchet-pawls being engaged for winding. Fig. 14 is a rear elevation of the mainspring-barrel, 70 from which most of the spring has been broken away, so as to expose the pawl which locks the mainspring-barrel to the arbor-sleeve, the pawl being shown retracted. Fig. 15 is a rear elevation of the exterior adjunct, the ratchet- 75 pawls being represented engaged. Fig. 16 represents a portion of the outside of the safe-door, the parts being in condition as follows, to wit: the mainspring-barrel locked to the arbor-sleeve and the ratchet-pawls disengaged, 80 so as to permit the setting up of the combination without allowing the spring to run down. Fig. 17 is a similar view to Fig. 14, but with the pawl engaged so as to lock the main barrel to the arbor-sleeve. Fig. 18 is an axial 85 section through the exterior adjunct. Figs. 19 and 20 are enlarged views of the parts represented by Figs. 1 and 10, respectively.

A may represent part of a safe-door furnished with usual or any suitable bolt-work, 90 B, and having a single orifice, *a*, Fig. 18, for the arbor C, whose inner extremity is made fast to the drive-wheel D of a customary or any suitable stack of tumblers, D', and whose square outer end protrudes through the door 95 and occupies a corresponding orifice in the winding stem or sleeve E, Fig. 18, which constitutes a part of my clock-work motive mech-

anism or exterior adjunct, to be presently described.

F may represent any suitable clock-work.

The inner end of mainspring G, Figs. 11 5 and 18, is attached to a winding stem or sleeve, E, and its outer end to housings or barrel H, whose ratchet-wheel I is provided with one or more pawls, J, Figs. 12 and 15, held in action by springs K, but capable of release by operating handles L of cams M.

Another pawl, O, pivoted to the inner wall of barrel H, and having a handle, P, enables the stem E to be locked fast to the barrel H when desired, it being necessary that these 15 members form a single piece when the purpose is to manipulate the tumblers or to throw or retract the bolt-work. The barrel H takes the form externally of a knob or handle, Q, Fig. 4, by means of which all the operations of the 20 lock controllable from the outside are governed.

The arbor C has geared connection R with the clock movement proper. (See Fig. 1.) A customary slack or stud connection of the two 25 systems of gearing is provided in order to permit the manipulation of the tumblers and bolt-work without interfering with the clock-work.

The clock-spindle W has separate pawl-and-ratchet connections X and Y with two disks, Z 30 and b, each having its own proper stud-projection, z and b', for independent impingement upon spring-detent c, which has a notch, c', that, when the timer is set or placed on guard, engages under a lug, d', that projects from the 35 angle-bar d, which is hinged or pivoted to the lock-wall at e, Figs. 2, 4, and 7, and has the customary arm, f, for engaging in the gates or notches of the tumblers, there being a small lip or projection, f', on the arm f, as shown 40 more clearly in Fig. 2, for a purpose to be presently explained.

In order to enable the bolt-work to be moved by means of the knob Q from the outside without having the tumblers set up or gated, I provide a bar or detached lever, h, (shown detached in Fig. 8,) which has at its front end a projection, i, adapted to engage with the drive-wheel D, as shown in Figs. 5 and 6, this lever being pivoted at its rear end to the bolt-work, as 50 shown at g, Fig. 19. To prevent this lever from engaging with the drive-wheel before the hour for opening has arrived, I secure to the face of this lever h a sliding latch, l, (shown detached in Fig. 9 and in position in Figs. 4 and 55 19.) A small spring, m, Figs. 4 and 9, is applied in such a manner as to keep this latch l pressed forward, in which case its front end engages upon the projection f' of the angle-bar, thus locking the lever h and the angle-bar d 60 together, so that the lever cannot engage with the drive-wheel, except when the tumblers are gated, in which case both the angle-bar and lever h drop together as one piece.

As shown in Figs. 7 and 19, the angle-bar is 65 provided with an arm, d', with which the spring-detent c engages until released by the pin z

of disk Z; but when the pin z is brought by the rotation of the disk against the detent c the latter is thrown back, so as not only to disconnect it from the arm d' of the angle-bar, but is 70 also forced against a pin, n', secured to the latch l, whereby the latch is drawn back off of the projection f', thereby unlocking the lever h from the angle-bar d, when the lever h is free to fall and engage with the drive-wheel, as 75 shown in Fig. 6, and when this occurs the bolt-work can be moved by turning the knob Q, even though the tumblers be not gated.

It will be observed that the pin b' of the disk b is so arranged or located in relation to the 80 pendent arm of the detent c that, while it will move the detent far enough to release the arm d' of the angle-bar, it will not move it far enough to draw back the latch l, as is represented in Fig. 3, the pin b' passing by and becoming clear of the detent before moving it far enough to draw back the latch. It follows from this construction and arrangement of parts that the disks b and Z may be so set that the pin b' will disconnect the 85 detent c from the angle-bar at any predetermined time, when by setting up the combination the door can be opened; but in case the combination formula has been lost or forgotten, or the person having charge of the combination should 90 be absent, then as the clock-work continues its movement the pin z will, in a given time for which it may have been set, force back the detent, draw back the latch, and release the lever h from the angle-bar, when, as above 95 stated, the door can be opened without gating the tumblers.

On the winding-stem E, I place a small pinion, n, (shown more clearly in dotted lines in Fig. 20,) which engages with a larger pinion, p, carrying on its face a graduated circle, and around the stem E is secured a stationary circle, r, which has an index or pointer, v, arranged to act in conjunction with the graduated circle on the pinion p, which serves to 100 show how far the spring has been wound up, and, reversely, how far it has unwound, motion being imparted to the pinions by the rotation of the stem E when the clock mechanism is in operation. Over the pinion n on the 105 stem E, I secure another index or pointer, t, which is arranged to turn within the stationary circle r, and which serves to indicate, in connection with a mark, s, on the circle, when the parts are in such a position as to permit the pawl O to engage with the stem E, these 110 parts being suitably arranged in relation to each other when they are put in place.

It will be seen by an examination of Figs. 14 and 17 that the pawl O can lock upon the 115 stem E whenever the latter is turned so as to cause either of its four sides or faces to stand in line with the rectangular notch in the pawl, and therefore it is only necessary to so locate the index t and the mark s as to show when 120 the stem and pawl are in that position.

As the index t is fast upon and turns with

the stem, it is obvious that there may be four of the marks *s* on the circle, as the pawl may engage with the stem when either of its four faces are turned toward the pawl. If, however, instead of making the stem square at the point where the pawl *O* engages it, it should simply be flattened on its two opposite sides, then of course there would be but two marks made on the circle.

10. By thus arranging the operating-spring within the dial or knob, as described, not only can it be got at in case of necessity without disturbing the lock or opening the door, but by disconnecting its barrel by means of the pawls *J* the knob is left free to be utilized both as a dial for manipulating the tumblers and also as a handle for throwing the bolt-work, thus avoiding the necessity of making two holes through the door. It is, however, obvious that, if preferred, the spring and its pawls may be put in a case separate and apart from the knob and still be accessible without opening the door or breaking into the safe. It is also obvious that, instead of the sliding latch *l* for locking the lever *h* to the angle-bar, other forms of devices may be used and be made to accomplish the same result, the only requisite being that the device used, whatever its form or construction may be, shall be arranged to lock the two parts together and be operated upon by the time mechanism to disconnect these parts at the proper time; and hence I do not limit myself to the use of these special devices, as any mechanic skilled in the art, from what is herein shown and described, can readily substitute other forms or devices for that purpose.

Having thus fully described my invention, what I claim is—

40. 1. In a combined time and non-time lock, the clock-work-motive apparatus, located exterior to the safe, substantially as described, whereby it is rendered accessible without disturbing the clock mechanism.
45. 2. In a combined time and non-time lock, the combination of the external mainspring

mechanism, consisting of mainspring *G*, barrel *H*, provided with ratchet-teeth, and pawls *J*, and winding-stem *E*, with pawl *O*, all arranged to operate substantially as described. 50

3. In a combined time and non-time lock, the combination of the drive-wheel *D*, the lever *h*, with its latch *l*, arranged to be released by the time mechanism, substantially as described, whereby the bolt-work is released from control of the combination mechanism at a predetermined time after the release of the combination from the domination of the timer, as and for the purpose set forth. 55

4. In a combined time and non-time lock, 60 the combination of the fence mechanism, consisting of the angle-bar *d*, lever *h*, and latch *l*, with the spring-detent *c* and its operating-disk *b* *b'*, substantially as set forth.

5. In a combined time and non-time lock 65 having the compound fence consisting of the parts *d*, *h*, and *l*, the spring-detent *c*, and the disk *Z* *z*, combined and arranged to operate substantially as and for the purpose set forth.

6. In a combined time and non-time lock 70 having its time-motor arranged exterior to the safe or vault, the index mechanism consisting of the parts *n*, *p*, and *v*, arranged to operate substantially as described.

7. In a combined time and non-time lock, 75 the index *t*, secured to and rotating with the winding-stem *E*, in combination with a fixed point, *s*, and the locking-pawl *O*, all arranged to operate as set forth.

8. A hollow safe-knob constructed substantially as described, whereby it is made to serve as a case for the mainspring and its connecting devices, as a dial for setting the tumblers, and as a knob or handle for moving the bolt-work, as set forth. 80

In testimony of which invention I hereunto set my hand. 85

WILHELM KOCK.
